UNITED STATES PATENT OFFICE

2,521,281

AUXILIARY RAISABLE CHAIR SEAT

René Brousseau, Montreal, Quebec, Canada, assignor to Better Seats Co., Montreal, Quebec, Canada

Application December 3, 1946, Serial No. 713,723

2 Claims. (Cl. 155—131)

1

The present invention relates to chair seats and, more particularly, such a seat adapted to be used in conjunction with a chair and raisable therefrom.

The main object of the invention, therefore, resides in the provision of improved means for increasing the effective height of a chair seat.

Another object is the provision of an auxiliary seat of the character described which is highly efficient and versatile for the purpose in view.

A further object concerns an auxiliary seat which is rigidly attachable to a chair in a removable manner.

Still another object contemplates a chair auxiliary seat which is rugged, simple and easy to adjust.

A still further object envisages a seat of the character described, which is easily produced at relatively low cost.

Other objects and advantages of the invention will become apparent, or be pointed out further, during the description to follow.

As an example, and for purposes of illustration only, an embodiment of the invention is shown in the annexed drawing, wherein:

Figure 1 is a side elevational view showing the invention in use,

Figure 2 is a perspective view of the auxiliary seat attached to an ordinary chair,

Figure 3 is a side elevational view of the seat of the invention,

Figure 4 is a detailed sectional view taken on line 4—4 of Figure 3,

Figure 5 is a partial front elevation view of one corner of the auxiliary seat, and

Figure 6 is a view similar to Figure 3, but showing, in enlarged form, the supporting means from the inside.

Referring to the drawings, wherein similar reference characters represent corresponding parts throughout, the reference letter C indicates generally an ordinary chair to which the auxiliary seat A of the invention is removably secured. As shown to advantage in Figures 1 and 2, the auxiliary seat is adapted to be adjustably elevated or lowered with respect to the chair C, the mechanism for effectuating this adjustment forming the subject-matter of the present invention.

The mechanism noted above consists essentially of a plurality of toggle joints J, one of which is secured to each corner of the auxiliary seat, said joints being connected in pairs to transverse spaced parallel base bars 10 resting on the seat of the chair C and removably secured thereto by special clamps 11 to be described later.

2

The toggle joints are secured to the seat A by means of a bracket 12 having a downwardly depending ear 13 to which ear the upper link 14 of the toggle joint is riveted or otherwise pivoted. The lower link 15 is in turn riveted at its lower end to a similar bracket 16 having an upstanding ear 17, said bracket being attached or secured adjacent the outer end of front and rear base bars 10—20 respectively, and adapted to join, each, the front toggles of the seat and the rear toggles thereof. The inner end of the links 14 and 15 are pivoted together by means of a bolt 19 having a tightening wing nut 21. Thus, from the mechanism described so far, it will be readily evident that the auxiliary seat A may be raised or lowered from the seat of the chair C whenever the toggle joints J are extended or collapsed.

The correct positioning of the toggles, in strictly similar angular relation between each other, is effected by means of spurs 25, one of which is associated with each toggle by pivoting one end thereof over the bolt 19 already disclosed and joining together the inner ends of the links 14—15; the lower end of the spur is cut at an angle to form a sharp edge adapted to engage the ratchet teeth 26 formed in the upper surface of a cross bar 27 disposed right angularly with respect to the bars 10—20, each of said cross bars 27 joining together in proper spaced relation the outer end of the base bars, so as to form a square frame.

The teeth 26 being symmetrically disposed with respect to the toggles, as shown clearly in Figures 2, 3 and 6, the extension of the toggles will be strictly identical at all corners provided the spurs are each engaged with the proper tooth, this adjustment being easily effectuated by counting or otherwise. For a purpose to be apparent later on, the cross bars 27 are provided with upstanding end flanges 28 the effective height of which above the bars 27 must be slightly more than the combined thickness of the joints J, spurs 25 and other mechanism when completely collapsed downwardly; in other words, the said flanges 28 act primarily as a stop against which the auxiliary seat A may rest when in its lowest position.

As already mentioned, the spurs 25 are useful for blocking inward movement of the toggles and also for correctly positioning the same; since, however, the said spurs are not effective to prevent outward movement of the toggles, tension arms 30 are also mounted on one end onto the pivot bolt 19, said arms converging centrally together towards the bracket 31 having the depending ear 32 supporting the screw 33. The outer

end of the arms is slotted to allow passage of the screw 33 therethrough, the arms being clamped together and to the ear 32 by means of a wing-nut 35.

Thus, the position of the toggles is at all times rigidly maintained by the spurs and also by the arms which additionally resist any tendency of the toggles to change their position. As a result, the elevating structure for the auxiliary seat A is a rigid linkage having great strength for supporting substantial weights and so interconnected as to sustain successfully any tipping tendency caused by applying a weight to the edge or a corner of the auxiliary seat.

The means for securing the frame of the auxiliary seat to an ordinary chair consist in the clamps 11 which are adapted to secure the frame to the seat of the chair C. For that purpose, the clamps in question engage toothed extension 40 formed at the end of the base bar 10 and a third extension 41 connected right angularly to the centre of the rear base bar 20. As shown to advantage in Figure 5, for instance, the clamps 11 have a yoke 45 engageable by the teeth of the extension, said engagement being maintained by a spring finger 46 contacting the underside of the seat of the chair C and adjustably secured to the yoke 45 by means of the screws 47 for adapting the clamp to varying thicknesses of chair seats.

From the foregoing description, the operation of the auxiliary seat should be fairly obvious: primarily, it is intended to serve as an attachment permitting the use of ordinary chairs by children who, otherwise, would not be able to sit properly at the dining table, for instance. Obviously the seat may be used by anyone for specific purposes although, in any case, the auxiliary seat "A" would have to be smaller than the seat of the chair to which it is attached so as to leave the necessary extension for clamping purposes and the like.

Due to the adjustable feature, the auxiliary seat is easily applicable to variously aged children, or used constantly by one child and adjusted downwardly in accordance with the growth of said child, thus giving him a new measure of confidence and allowing him to acquire early proper table manners with adults.

From the foregoing it must be realized that the present invention is an advance of the art in that it provides an adjustable auxiliary seat

which is strong, easily adjustable and which, once adjusted remains rigidly in position without tipping or other deformation tendencies. Again, the said auxiliary seat may be quickly adapted for attachment to ordinary chairs without marring same or necessitating drilling, nailing or other defacing operations.

It must be understood various changes as to the shape, size and arrangement of parts may be resorted to without departing from the spirit of the invention or the scope of the subjoined claims.

Having thus described my invention, I claim:

- 15 1. In an auxiliary seat for a chair, adjustable in height relative thereto, a quadrangular frame securable to the chair, a pair of toggle links at each corner of said frame, an auxiliary seat supported by said links, the links of each pair being pivoted together and at their outer end to the frame and seat respectively, arms pivoted to the links pivots and meeting in pairs centrally beneath the seat, and means for releasably clamping said arms in pairs to prevent outward spreading of the toggle links.
- 20 2. In an auxiliary seat for a chair, adjustable in height relative thereto, a quadrangular frame securable to the chair, a pair of toggle links at each corner of said frame, an auxiliary seat supported by said links, the links of each pair being pivoted together and at their outer end to the frame and seat respectively, arms pivoted to the links pivots and meeting in pairs centrally beneath the seat, means for releasably clamping said arms in pairs and to said seat to prevent outward spreading of the toggle links, and means 30 limiting movement of the links inwardly.
